UNITED STATES PATENT OFFICE

104,706

DESIGN FOR A STEERING WHEEL DEVICE

John Sinko, Oak Park, Ill.

Application October 24, 1936, Serial No. 65,489

Term of patent 7 years

To all whom it may concern:

Be it known that I, John Sinko, a citizen of the United States residing at Oak Park, county of Cook, and State of Illinois, have invented a new, original, and ornamental Design for a Steering Wheel Device, of which the following is a specification, reference being had to the accompanying drawing forming a part thereof, in which:

Figure 1 is a side elevational view of a steer-

ing wheel device embodying the invention, the dotted lines indicating a knob; Fig. 2, a front elevational view of the same; and Fig. 3, a plan view.

The characteristic feature of my design resides in the beaded rim-clamping element.

I claim:

The ornamental design for a steering wheel device, as shown and described.

JOHN SINKO.
